UNITED STATES PATENT OFFICE.

CHARLES M. MUCHNIC, OF PHILADELPHIA, PENNSYLVANIA

COMPOUND LOCOMOTIVE-ENGINE.

SPECIFICATION forming part of Letters Patent No. 705,692, dated July 29, 1902.

Application filed March 29, 1901. Serial No. 53,449. (No model.)

To all whom it may concern:

Be it known that I, CHARLES M. MUCHNIC, a citizen of the United States, residing at Philadelphia, in the county of Philadelphia and State of Pennsylvania, have invented 5 certain new and useful Improvements in Compound Locomotive-Engines, of which the following is a specification.

The objects of my invention are to eliminate 10 objectionable features from existing four-cylinder two-crank compound locomotives, such as excessive bending load on the piston- rods, which tends to tip the cross-head; to dispense with excessive counterbalance and 15 reciprocating weights, which when at high speed are a decided detriment to the permanent road and cause what is commonly termed the "hammer-blown;" to provide a more properly balanced and uniformly rotative 20 mechanism and effect a saving of the road and machinery and insure comfort to passengers; to accomplish the above conditions with the utmost simplicity of parts and with the least possible deviation from the existing 25 standard of American locomotive construction, so that the transformation of a single-acting outside-connected locomotive-engine of any class or service to a compound can be very easily effected; to provide, as in a single-acting outside-connected engine, but one 30 valve-motion for each side of the locomotive-engine actuating one valve, and to provide an improved valve which can also be applied to compound locomotives and also to 35 marine and stationary compound engines where similar conditions exist.

The invention consists of the improvements hereinafter described and claimed.

The nature, characteristic features, and 40 scope of the invention will be more readily understood from the following description, taken in connection with the accompanying drawings, forming part hereof, and in which—

Figure 1 is a diagrammatic side view of a 45 locomotive-engine embodying my improvements. Fig. 2 is a sectional plan view drawn to an enlarged scale and illustrating the forward portion of the locomotive shown in Fig. 1 and also illustrating the arrangement of cylinders 50 and the respective position of high and low pressure pistons, with their connections to the internal and external cranks. Fig. 3 is

a sectional view drawn to an enlarged scale and taken on the line 1 2 3 of Fig. 7 and showing the single piston-valve, cylinders, pistons, 55 &c. Fig. 4 is a sectional view taken on the line 4 5 of Fig. 7, showing the valve-bushing, the intercepting-valve, and its communication with the high-pressure exhaust. Fig. 5 is a sectional view taken on the line 6 7 of 60 Fig. 7 and showing the device for admitting live steam from the boiler into the low-pressure steam-inlet ports when the engine starts from a period of rest or when working all cylinders single expansion. Fig. 6 is a sectional 65 view taken on the line 8 9 of Fig. 4 and showing the communication of the intercepting-valve with the low-pressure steam-inlet ports. Fig. 7 is a transverse sectional view taken on the line 12 13 of Fig. 4 and showing the left-hand cylinder-casting, and Fig. 8 is a transverse sectional view taken on the line 10 11 of Fig. 4 and showing the right-hand cylinder-casting.

A in Figs. 1 and 2 is the body of the locomotive; B, the cylinder-casting; C, the longitudinal side frames; D, the high-pressure cylinder; E, the low-pressure cylinder; H H, the driving-wheels; G, the cranked driving-axle; I, the outside crank; J, the inside 80 crank; K, the inside connecting-rod; L, the outside connecting-rod; M, the low-pressure piston-rod; N, the high-pressure piston-rod; O, the high-pressure piston; P, the low-pressure piston, and Q the valve-rod.

The cylinder-casting B, reference being made particularly to Figs. 7 and 8, comprises one high-pressure cylinder E, one low-pressure cylinder D, a valve-chamber V, an intercepting-valve chamber U, steam induction 85 and eduction ports for both high and low pressure cylinders a b c d, Figs. 3 and 4, high-pressure exhaust passages and chamber Z Z', low-pressure admission-passages T T', main live-steam passage R, which communicates in the usual way with the dome of the boiler, and final exhaust-passage S, which communicates in the usual way with the exhaust-pipe in the smoke-box. It will be noticed from Figs. 7 and 8 that the cylinder-castings B, or what are technically termed the "cylinder-saddles," are to be bolted together, fixed to the frames C, and attached to the boiler in precisely the same manner as the

usual cylinder-saddles of the modern locomotive. I can therefore remove the two saddles with their high-pressure outside cylinders of the usual locomotive and substitute in their place my improved compound cylinder-saddles. As said before, the high-pressure cylinder E, low-pressure cylinder D, valve-chamber V, and intercepting-valve chamber U are cast in one piece with the 5 "saddle," and the whole forms the cylinder-casting B. The high-pressure cylinder E is shown as cast in the portion of cylinder-saddle extending inside the side frames, and the low-pressure cylinder D is cast outside the 10 side frames; but this arrangement may be reversed, if found desirable. Both cylinders are shown to be in the same horizontal plane; but the interior cylinders may be made 15 slightly inclined to the horizontal plane or somewhat above the horizontal axis of the outside cylinders when it is desired to have the inside connecting-rods K, Fig. 2, clear a forward axle. The valve-chamber V is cast 20 as near the cylinders as practicable and may be lined with a cast-iron bushing Y, having slotted openings dressed accurately to the required sizes. The valve F, Fig. 3, is of the closed-piston type and receives its motion 25 from a link and rock-shaft in the usual way. A valve-rod Q passes through the valve F and is guided in the stuffing-boxes of valve-chamber covers l and m. The rear end of Q is 30 prolonged to make connections with Q' and rock-shaft. The valve is provided with cast-iron packing-rings n to make a steam-tight 35 joint between the valve and the bushing, so as not to allow the escape of steam from one portion of the valve to the other. This compound valve is both of the internal and external admission for high and low pressure 40 cylinders, respectively. Of course the order may be reversed, if desired.

The intercepting-valve U, Figs. 4, 6, and 7, is a plain cast-iron cylinder open at one end. It has three openings cut out—two at the ends, e and f, and one, g, equidistant from e and f and diametrically opposite them. These openings are so arranged that either the openings e and f or g can be in communication with T and T' or g' R, respectively, and cannot be all open simultaneously. The intercepting-valve U is provided at the blind end with a rod r, which passes through a stuffing gland or box s. r is to be connected with a combination of levers and rods extending into the cab for turning the intercepting-valve U when changing the engine from simple working into compound, and vice versa. This valve can be worked by automatic devices, if 60 desired.

The working of the compound system will be readily understood from reference to Fig. 3. The closed-piston valve F, which has moved from its central position toward the left, has 65 uncovered the high-pressure induction-port a, through which live steam from the boiler, coming by way of the main live-steam pas-

sage S, (see also Fig. 8,) penetrates into the high-pressure cylinder D and pushes the piston O to the right. At this movement the 70 volume of steam contained from the previous forward stroke in cylinder D between the back cylinder-cover h and the rear side of piston O is forced through port b into the high-pressure exhaust-passage Z and thence (see 75 Fig. 4) into the intercepting-valve U. It will be noticed in Fig. 3 that the displacement of the valve to the left has uncovered simultaneously with the high-pressure induction-port a also the low-pressure induction-port c, 80 through which the steam contained in the intercepting-valve U penetrates into the low-pressure cylinder E. In other words, the high-pressure exhaust-steam goes directly into the low-pressure cylinder E, and there the steam 85 forces the piston P forward, or in the opposite direction of the high-pressure piston O. At this movement the volume of steam contained from the previous backward stroke between the front cylinder-cover k and piston 90 P is forced through the port d into the final exhaust-passage R (see also Fig. 7) and thence into the smoke-stack. It can be now readily understood that the valve F on its return or backward stroke will uncover the ports b and 95 d, the high and low pressure induction-ports, respectively, and the steam from the high-pressure cylinder will exhaust through port a and exhaust-passage Z' and will pass, as before, into the intercepting-valve U, thence 100 through the intercepting-valve opening e and low-pressure steam-admission passage T. The steam from the high-pressure cylinder D will 105 pass through induction-port d into the low-pressure cylinder E. The volume of steam contained in cylinder D from the previous stroke will escape through port c into the final exhaust-passage R and thence to the stack—that is, the cycle performance of the 110 steam from passages E to R will be the same as in the previous case, but reversed in order. When the locomotive is required to start a heavy train or to pull it over sections of road with steep short grades or when the usual hauling capacity of the locomotives fails to 115 haul the train over the difficult section of the road or to sustain the desired speed, all four cylinders can then be made to work single 120 expansion, thus almost doubling the tractive power of the locomotive-engine. This condition I bring about in the following manner, reference being had particularly to Figs. 4, 125 5, 6, and 7: The intercepting-valve U is given a half-turn, which cuts off all communication between intercepting-valve U and low pressure admission-passages T and T'—in other words, between the high and low pressure cylinders—but by the same movement of the intercepting-valve U a communication is established between the final exhaust-passage 130 R and the intercepting-valve U through the openings g in the intercepting-valve and G' in the cylinder-casting B, which then are in alignment with each other. In other words,

a direct communication is established between the high-pressure exhaust passages and chamber Z, Z', and Z² or high-pressure cylinder D and the final exhaust-passage R. 5 When the steam from the high-pressure cylinder E thus exhausts directly into the smoke-stack without passing through the low-pressure cylinder D, live steam from the boiler is admitted directly into the low-pressure admission-passages T and T' through pipes X and W, Fig. 5. The admission of steam into pipe X, which is connected to the dome of the boiler or to the steam-pipe bringing steam to passage S, is under full control of the locomotive-engineer in the cab, and this may be done by the manipulation of a simple valve or three-way cock. Since the pistons of each high and low pressure cylinder on each side of the locomotive actuate an interior and exterior crank, respectively, and are so arranged as to produce movements of the pistons in opposite directions, they practically balance each other, together with the horizontally-moving masses they operate upon. 15 It will be obvious to those skilled in the art to which the invention relates that modifications may be made in details without departing from the spirit thereof. Hence I do not limit myself to the precise construction and arrangement of parts hereinabove set forth, and illustrated in the accompanying drawings; but, 25

Having thus described the nature and objects of the invention, what I claim as new, 30 and desire to secure by Letters Patent, is—

1. In a compound locomotive-engine the combination of high and low pressure cylinders, a single valve-chamber common to both cylinders, a single steam-distribution valve 40 common to both cylinders and which always prevents the passage directly through itself of steam from the high to the low pressure cylinder, an intercepting-valve chamber, a steam-inlet to the valve-chamber, a steam-exhaust 45 from the valve-chamber, passages from the valve-chamber to the high-pressure cylinder and to the intercepting-valve chamber and to the low-pressure cylinder and to exhaust whereby a path is established for steam to 50 pass to the high-pressure cylinder and thence to the intercepting-valve chamber by way of the valve-chamber, and an intercepting-valve for passing steam received from the high-pressure cylinder directly to exhaust or low-pressure cylinder by way of the valve-chamber so that the engine can run either single or compound, substantially as described. 55

2. In a compound locomotive-engine the combination of high and low pressure cylinders, a single valve-chamber common to both cylinders, a single steam-distribution valve common to both cylinders and which always prevents the passage directly through itself of steam from the high to the low pressure cylinder, an intercepting-valve chamber, a steam-inlet to the valve-chamber, a steam-exhaust 60 from the valve-chamber, passages from the

valve-chamber to the high-pressure cylinder and to the intercepting-valve chamber and to the low-pressure cylinder and to exhaust, 70 whereby a path is established for steam to pass to the high-pressure cylinder and thence to the intercepting-valve chamber by way of the valve-chamber, an intercepting-valve for passing steam received from the high-pressure cylinder to exhaust or low-pressure cylinder by way of the valve-chamber, and means for introducing live steam to low-pressure cylinder by way of its ports in the distribution-valve to run both cylinders single expansion, 75 substantially as described. 80

3. The combination of the described cylinder structure comprising high and low pressure cylinders, and steam-passages and admission-passages and a main exhaust, a steam-valve, an intercepting-valve consisting of a cylinder open at one end and having three openings cut on its circular surface and so arranged with respect to the steam-passages in the cylinder structure that by a turn of said intercepting-valve the high-pressure exhaust will either communicate with the admission-passages of low-pressure cylinder or with the main exhaust-passage from low-pressure cylinder to stack, thus enabling the engineer to 90 change the working of the engine from compound into single expansion, and vice versa, substantially as described. 95

4. The combination in a cylinder structure for compound locomotive-engines, of passages T T' for admitting steam from the distribution-valve to the low-pressure cylinder and a passage W communicating with both passages T and T' and whereby live steam is introduced into those passages, high and low pressure cylinders, a steam-distribution valve common to both cylinders and having its low-pressure-cylinder ports communicating with the passages T T', a distribution-valve having provisions for always preventing direct communication through it between the two cylinders, and a steam-pipe X, substantially as described. 100 105

5. The combination in a compound locomotive, of a high-pressure cylinder, a low-pressure cylinder, a single steam-distribution valve common to both cylinders and having provisions for the independent admission and exhaust to both cylinders and having provisions for always preventing direct communication through it between the two cylinders, an intercepting-valve for directing exhaust steam from the high-pressure cylinder directly to the admission portions of said distribution-valve that appertain to the low-pressure cylinder or directly to the exhaust provisions of said distribution-valve, and a steam-supply to the admission portions of said distribution-valve that appertain to the low-pressure cylinder, substantially as described. 115 120 125 130

6. The combination with a compound locomotive having high and low pressure cylinders and their complementsal single steam-dis-

tribution valve having provisions for always preventing direct communication through it between the two cylinders, of an intercepting-valve and its connections for receiving the 5 exhaust from the high-pressure cylinder by way of the distribution-valve and passing it directly to the main exhaust or directly to the parts of said distribution-valve that appertain to the low-pressure cylinder, whereby 10 the engine may be run either single or compound, substantially as described.

7. The combination with a compound locomotive having high and low pressure cylinders and the single steam-distribution valve 15 common to both and having provisions for always preventing direct communication

through it between the two cylinders, of a steam-admission pipe X and proper connections to the boiler for admitting steam to the parts of the distribution-valve which appertain to the low-pressure cylinder, and means for causing exhaust direct from the high-pressure cylinder, whereby the low-pressure cylinder can be run with live steam, substantially as described. 20

In testimony whereof I have hereunto signed my name. 25

CHAS. M. MUCHNIC.
